FIG. 4, August 9th 1845
Era Ripley

Des. 41

Ezra Ripley assignor to Johnson Geer & (Geo) Hoy
N.Y. Seller's Patent (Design No. 41) Dated 16th October 1845.
(Antedated 14th August 1845)

The schedule referred to in this Seller's Patent and making
part of the same.

To all whom it may concern Be it known that I Ezra Ripley
of the City of Troy, County of Rensselaer and State of New York
by my own industry, genius and expense have invented and pro-
duced a new and original design shape Configuration and pattern
of two stone plates to be used in the manufacturing of air tight
or box stoves.

The nature of my invention consists in the peculiar configura-
tion and ornamental carved work on the outer surface of the top &
side plates of the stove.

It is impossible to describe accurately in language the ornamen-
tal carvings on the surface of the plates but the same is represented
as accurately as possible in the Engraving, or Drawings hereto annexed.
Fig 1st in the Drawing represents the top Plate. It may be made of any
convenient size, and is of an oblong shape. The carvings on the surface
are elevated & depressed and consist of Rossets, scrolls, Diamonds, leafs
and other fancy carvings arranged as represented in the figure. Fig 2 in
the Drawing represents the side plates. It may also be made of any
convenient size, and is nearly square. The carvings on the surface are
designed to represent the front of a Gothic Cottage, with two large
Gothic windows extending from the bottom upward to near the top as
seen at G.G in the fig & are surrounded with Gothic mouldings in-
terspersed with Rossets & head, on the other sides of each of these large
windows is two smaller windows as represented at a,a,a,a, (in the
figure) these are also surrounded with Gothic ornaments, near the
centre of the plate & between the two large windows is another
small window as represented at C (in the fig) under this small

Des. 41

2

window is represented a door surrounded also with gothic ornaments as seen at D. (in the fig.)

What I claim in my invention and desire to secure by letters patent is the peculiar style of ornamental carving on the surface of the plate, and the peculiar elevations and depressions of the surface as represented in the drawings.
